UNITED STATES PATENT OFFICE.

BERNARDO C. HECHAVARRIA AND MIGUEL A. MONTEJO, OF NEW YORK, N. Y.

HEAD-WEAR.

SPECIFICATION forming part of Letters Patent No. 272,136, dated February 13, 1883.

Application filed June 21, 1882. (Model.)

To all whom it may concern:

Be it known that we, BERNARDO C. HECHAVARRIA and MIGUEL ANTONIO MONTEJO, citizens of the United States of North America, 5 and residents of the city, county, and State of New York, have invented a new and useful Improvement in Head-Wear, of which the following is a specification.

The object of this invention is to provide a 10 lighter, better ventilated, more inexpensive, and naturally-ornamented article of head-wear.

The invention consists of a hat, cap, or bonnet made from the fibrous linings of the seed-pods of a plant or vine, and preferably of a 15 vine known locally in the Island of Cuba as the "estropajos" or "friega platos," belonging to the botanical family cucurbitacæ, genus luffa, specific name *Cucumis acuteangularia* or *Cucumis angulata*.

20 Figure 1 represents a seed-pod, partly in section, of the *Cucumis angulata*. Fig. 2 represents the inner lining of a seed-pod of the same, spread open. Fig. 3 represents a bonnet or hat made from seed-pod linings of the same.

25 Similar letters of reference indicate corresponding parts.

The seed-pod consists of an outer covering, A, which, when dry, is readily detachable from the fibrous lining B, which latter is composed 30 of a net or lace work, a, of interlaced fibers of extreme lightness and considerable strength, from which at regular intervals three longitudinal rows, b, of fibrous seed-cells containing seeds c project inward. The covering A being 35 removed, the lining B is split longitudinally and spread open, and the seeds c removed, as shown in Fig. 2.

To make a hat, cap, or bonnet, the linings B are cut into the desired shapes and sewed 40 together, preferably over and on a frame or body, C, of buckram or other suitable fabric, and said hat, cap, or bonnet is then further stiffened or shaped by means of wires or other devices usually adopted in the manufacture of straw goods. On the bonnet or other article 45 the seed-cells b form ornamental open-work ribs that give a unique appearance thereto, and are sufficient to distinguish it from any

other article of head-wear. These fibrous linings B may be used in their natural condition, 50 or may be bleached or colored, if desired. The vine from which this material is obtained grows in great profusion in the Island of Cuba, and produces seed-pods of from one to twelve inches or more in length, and of from two to twelve 55 inches or more in circumference. No braiding or other manipulation of the lining B is required to prepare it for formation into various articles of head-wear, the said linings simply being cut into shapes and sewed together; hence, it 60 will be seen that they can be made up into hats, caps, or bonnets at much less expense than straws or grasses or other fibrous vegetable substances now in use for such purposes.

Other seed-pod linings of somewhat similar 65 formation having projecting rows or ribs of seed-cells may be substituted for those herein shown and described in the manufacture of head-wear without departing from the spirit of our invention.

Having thus described our invention, we 70 claim as new and desire to secure by Letters Patent—

1. As an improved article of manufacture, a hat, cap, or bonnet made from the fibrous 75 inner lining of the seed-pod of the plant or vine known as the *Cucumis angulata*, as set forth.

2. An article of head-wear made by sewing together the fibrous linings of seed-pods having 80 projecting ribs or rows of seed-cells, substantially as herein shown and described.

3. An article of head-wear made in whole or in part from the fibrous inner lining of the seed-pod of the vine known as the "estropajos" 85 or "friega platos," substantially as set forth.

In testimony that we claim the foregoing as our invention we have signed our names, in presence of two witnesses, this 9th day of June, 1882.

BERNARDO C. HECHAVARRIA.
MIGUEL ANTONIO MONTEJO.
